[57] **CLAIM**

The ornamental design for a display sign, as shown and described.

DESCRIPTION

FIG. 1 is a front elevation view of the display sign of the present invention;

FIG. 2 is a back elevational view of the display sign of FIG. 1;

FIG. 3 is a left side elevational view of the display sign of FIG. 1;

FIG. 4 is a right side elevational view of the display sign of FIG. 1;

FIG. 5 is a top plan view of the display sign of FIG. 1; and, FIG. 6 is a bottom plan view of the display sign of FIG. 1. The broken lines are shown for illustrative purposes only and form no part of the claimed design.
